CHRISTMAS CARD HOLDER

Mary Z. Hovlid, Long Beach, Calif.

Application April 22, 1957, Serial No. 45,820

Term of patent 14 years

(Cl. D29—1)

FIG. 1

I claim:

The ornamental design for a Christmas card holder, substantially as shown.
